UNITED STATES PATENT OFFICE.

JAMES A. BOZE, OF WAXAHACHIE, TEXAS.

TELEPHONE-LIGHTING SYSTEM.

1,113,537.

Specification of Letters Patent. Patented Oct. 13, 1914.

Application filed April 14, 1913. Serial No. 760,891.

To all whom it may concern:

Be it known that I, JAMES A. BOZE, a citizen of the United States, residing at Waxahachie, in the county of Ellis and State of Texas, have invented certain new and useful Improvements in Telephone-Lighting Systems, of which the following is a specification.

This invention as specified relates to new and useful improvements in telephone lighting systems.

The object of the invention is to provide lamps on subscribers' telephones arranged so that when a subscriber removes the receiver from the switch hook the lamp on his telephone will light and as soon as he has completed his connection with a called party, the lamp on the called telephone will light and will remain lighted after said called party removes his receiver from the switch hook. The lamp on the called party's telephone being extinguished when he replaces his receiver, but the lamp on the calling party's telephone burning until he replaces his receiver.

A further object is to provide such a system without changing or adding to the line circuit and to install said system by the use of a minimum number of parts.

A still further object of the invention is to provide a device of the character described that will be strong, durable, efficient and simple and comparatively inexpensive to construct, also one in which the several parts will not be likely to get out of working order.

With the above and other objects in view, the invention has relation to certain novel features of construction and operation, an example of which is described in the following specification and illustrated in the accompanying drawings, wherein:

Figure 1 is a circuit diagram of the system, Fig. 2 is a perspective view of a telephone equipped with the lamp, Fig. 3 is a plan of the lamp shade and clamp, and Fig. 4 is a side view of the clamp and shade, the latter being illustrated in section.

Referring to Fig. 1 of the drawings the numerals 1 and 2 indicate the positive and negative wires respectively, of an automatic telephone line circuit. In this figure I have shown only the circuits at one subscriber's station, but it is to be understood that the circuits at all stations will be the same and the invention will be clearly understood by a

detailed description of Fig. 1. The line wires have connection in the usual way to the ringing circuit wires 3 and 4 and the common return wire 5. A condenser 6, bell 60 7 and switch hook 8 are connected in series in the ringing circuit in the ordinary manner. Connection is made with the switch hook by a contact 9 on the ringing side and by a contact 10 on the talking circuit side. 63 The usual talking circuit comprises the wires 11, 12, 13, 14 and 15 respectively, the calling switch 16, transmitter 17 and receiver 18, being connected in series in said circuit and the wires 11 and 15 being connected to 70 line wire 1 and contact 10 respectively.

I have described the ordinary subscriber's station equipment and the same forms no part of my invention, which is merely used in connection therewith.

To the wire 3 connection is made by a wire 19 which leads to a contact 20 in position to be engaged by the contact 10, but normally out of contact therewith. A lamp 21 is connected in series with this wire which 80 forms one side of an auxiliary lighting circuit. When the calling party removes the receiver from the switch hook 8, the latter breaks contact with contact 9 and contacts with contact 10 thus closing the talking circuit at his station. The contact 10 contacts with the contact 20 thus closing the auxiliary circuit over wire 19 and through the lamp 21, which now burns.

We will suppose the bell 7 to be located at 90 the called station which has the same equipment. A wire 22 leads from the wire 19 to a bracket 23 on the bell. A light coil spring 24 has its upper end attached to the bracket and its lower end connected 95 with a pivoted contact 25 normally holding the same out of contact with a steel contact 26 projecting from a steel ring 27 mounted on the core of the adjacent magnet. A wire 28 leads from the contact 26 to a point of connection with the wire 4 of the ringing circuit. The wire 22, spring 24 and wire 28 forms part of the auxiliary lighting circuit.

In the wire 28 a resistance coil 29 is connected in series. It is to be understood that the parts just described are to be installed at all subscribers' stations. The calling party having lighted his lamp as described, calls his party. When the connection at the called party's station is completed, his ringing circuit is closed, the magnets of his bell being energized which causes the contact 26 105 110

to attract the contact 25, overcoming the tension of the spring 24. In this way the auxiliary circuit is closed through the wire 19, lamp 21, wire 22, bracket 23, spring 24, 5 contacts 25 and 26, wire 28 and coil 29 to the ringing circuit wire 4. The called party's lamp is thus lighted. It is obvious that when the called party removes his receiver his lamp will still burn the same as 10 the calling party's lamp and will only be extinguished when he replaces his receiver; the same thing being true at the calling party's station.

Having described the circuit, a description 15 of the lamp will now be given, however, it is obvious that the lamp may be located at any desirable point on the telephone and arranged in any convenient and advantageous manner as the principle of the invention 20 is to provide a lamp and light the same by the usual operation of the subscriber's telephone set. In an automatic telephone the lamp will of course be used to illuminate the calling switch dial and may be arranged to furnish light for observing the 25 telephone directory book and other purposes.

In Figs. 2, 3 and 4 I have shown an example of telephone lighting and to which my invention is not limited. A two membered clamp ring 30 is arranged to embrace the post of a telephone and receiving at one side the lug 31 of a lamp shade 32. The lug is held between the clamp members by a thumb-bolt 33, while diametrically opposite, a thumb-bolt 34 is employed to clamp the ring on the post. Within the shade the lamp 21, as indicated in Fig. 1, is suitably mounted and connected as described, by the wire 19, which is brought out through the 30 telephone post. By adjusting the thumb-bolts 33 and 34 the lamp may be adjusted on the telephone post and also the shade may be swung to throw the light on the switch dial or in front of the same.

It is to be noted that while the lamps burn in harmony with the talking circuit said lamp circuit depends merely upon its contact 20 coöperating with the contact 10 of the talking circuit.

What I claim, is:

1. In a subscriber's telephone set lighting system, the combination with the ringing and line circuits, of an auxiliary lamp con-

nected with said circuits and arranged to burn when said circuits are closed. 55

2. In a subscriber's telephone set lighting system, the combination with the ringing and line circuits, and the bell-coils thereof, of a lamp connected with said circuits and coils arranged so that a circuit through said lamp is closed when said coils are energized. 60

3. In a subscriber's telephone set lighting system, the combination with the ringing and line circuits, the switch hook, and the bell coils, of a contact coöperating with the talking circuit contact of the switch hook, a pair of normally open contacts associated with the bell coils, and a lamp connected with contacts named and also connected with said circuits. 65

4. In a subscriber's telephone set lighting system, the combination with the ringing and line circuits, of an auxiliary lamp connected with said circuits and arranged to burn when said circuits are closed, and a 70 resistance element in series with said lamp.

5. In a subscriber's telephone set lighting system, the combination with the ringing and line circuits and the switch dial, of an auxiliary lamp connected with said circuits 80 and arranged to burn when said circuits are closed, said lamp being located in position to illuminate the switch dial of an automatic telephone.

6. In a subscriber's telephone set lighting 85 system, the combination with the ringing and line circuits, the switch hook, and the bell coils, of a pair of magnetic contacts associated with the bell coils, a resilient member normally holding said contacts 90 open, a circuit connection between one of said magnetic contacts and the ringing circuit, a circuit connection between one of said magnetic contacts and one side of the line circuit, an auxiliary contact coöperating 95 with the talking circuit contact of the switch hook, and a lamp having circuit connection with the auxiliary contact and the magnetic contact circuit connection.

In testimony whereof I have signed my 100 name to this specification in the presence of two subscribing witnesses.

JAMES A. BOZE.
